UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO.

CAR-COUPING.

1,104,516.

Specification of Letters Patent. Patented July 21, 1914.

Application filed February 18, 1913. Serial No. 749,113.

To all whom it may concern:

Be it known that I, HARRY T. KRAKAU, a citizen of the United States, residing at Cleveland, Cuyahoga county, Ohio, have invented new and useful Improvements in Car-Couplers, of which the following is a specification, reference being had to the accompanying drawings, in which—

Figure 1 is a plan view of the coupler head and knuckle, a portion of the coupler head being shown in section. Fig. 2 is a section on lines II—II of Fig. 1, and Fig. 3 is a section on lines III—III of Fig. 1.

My invention relates to car couplers, and provides a coupler in which the major portion of the pulling strains is carried back through the knuckle tail and is thence transmitted to the coupler head, and in which the knuckle pin is relieved of strain, thus enabling the hub of the knuckle and the ears of the coupler head to be made of heavy section through the utilization of a smaller pivot pin.

My improvements consist in the construction of the knuckle tail and of corresponding parts on the coupler head through which the pulling strains are transmitted, and in provision for holding the knuckle tail from vertical movement relative to the coupler head, whereby creeping of the lock is prevented.

Referring to the drawings, A indicates the coupler head, B the knuckle, C the lock, and D the knuckle pin. The knuckle tail 2 has projecting vertically from its upper and lower faces transversely-extending lugs 3 and 4, which engage corresponding shoulders 5 and 6 on the top and bottom of the coupler cavity respectively when the knuckle is in locked position. The forward or bearing walls of the lugs 3 and 4 are curved and the arcs of curvature are struck from centers which are out of coincidence with the center of the pivot pin D; that is, the center of rotation of the knuckle B. The purpose of this eccentricity is to prevent friction, which would retard the opening movement, between the lugs 3 and 4 and the shoulders 5 and 6 as the knuckle B revolves about the pin D, so that the lugs will immediately free themselves from the shoulders, and thus permit an easy and unretarded swinging of the knuckle. Regardless of whether or not the rear face 7 of the knuckle wears and 55 allows the knuckle tail to move farther in-

wardly against the side wall 8 of the coupler head, the lugs 3 and 4 will always remain in tight contact with the shoulders 5 and 6 for transmitting the pulling strains and relieving the pivot pin of strain because 60 of the eccentricity of the centers of curvatures of the lugs and shoulders with respect to the center of the pivot pin.

The lock C is preferably of wedge shape in vertical cross section, to hold the knuckle 65 tight in its bearings against the wall 8 and the shoulders 5 and 6, and to compensate for wear, but if desired may be made with parallel sides and without the wear-compensating feature.

The upper and lower surfaces 9 and 10 of the lugs 3 and 4 respectively are slightly convergent toward the rear side of the knuckle tail, as is shown in Fig. 3, and the coupler head has correspondingly inclined surfaces 75 11 and 12, which, when the knuckle is in locked position, are just in contact with the surfaces 9 and 10. This contact, which extends clear across the knuckle tail, tends to hold the tail against any vertical movement, 80 and so eliminates the usual cause of the creeping of the lock. The rear side 7 of the knuckle tail contacts with the bearing 8 on the side wall of the coupler cavity when the knuckle is in locked position, such contact 85 taking place before the surfaces 9 and 10 come into excessive wedging engagement with the corresponding inclines 11 and 12, but not before they are in contact, or so nearly so that they will effectually prevent 90 any vertical movement of the knuckle tail. When the knuckle is swung open, the inclination of the surfaces 9 and 10 causes them to move away from the corresponding inclines 11 and 12 of the coupler cavity to 95 practically the same degree that the bearing faces of the lugs 3 and 4 move away from the shoulders 5 and 6, thus insuring an unretarded opening of the knuckle.

It will be seen that the strains of buffing 100 and draft are transmitted equally through both the top and bottom of the coupler head by reason of the location of the lugs 3 and 4 and the corresponding shoulders 5 and 6, thus obtaining a proper distribution of the 105 pulling strains, and preventing any vertical distortion of the knuckle tail.

It is obvious that various changes may be made in the construction and operation of the coupler which I have described and 110

shown herein without departing from my invention, since

What I claim is:

1. In a car coupler, a coupler head, a knuckle, a wedge lock, said knuckle having the upper and lower surface of its tail inclined in a transverse direction, said inclines converging toward the rear side of said tail, corresponding inclines on the coupler head, and means on the coupler head co-acting with the knuckle tail to prevent excessive wedging of said inclines but permitting their contact to prevent vertical movement of said knuckle relative to the head, the said lock being adapted to hold the inclines on the knuckle tail in wedging engagement with the inclines on the coupler head.
2. In a car coupler, a coupler head, a knuckle, a wedge lock, said knuckle having on its upper and lower surfaces inclines convergent toward the rear side of its tail co-acting with corresponding inclines on the

coupler head, and a vertical bearing surface on the rear side of said knuckle tail in contact with a corresponding bearing on the coupler head to prevent excessive wedging of said inclines, the said lock being adapted to hold the inclines on the knuckle tail in wedging engagement with the inclines on the coupler head.

3. In a car coupler, a coupler head, a knuckle having a tail with a vertical rear side, inclines upon the upper and lower surfaces of said tail, said inclines extending transversely across the width of said tail and being convergent toward its rear side, and a wedge lock, the said lock being adapted to keep the inclines upon the tail in engagement with corresponding inclines upon the head.

HARRY T. KRAKAU.
